UNITED STATES PATENT OFFICE.

JOHN JAMES RATHBONE, OF LONDON, ENGLAND, ASSIGNOR OF TWO-THIRDS TO ERIC RIVERS SMITH AND CHARLES BEAN KING, JR., OF SAME PLACE.

ELECTRIC-ARC LAMP.

SPECIFICATION forming part of Letters Patent No. 660,393, dated October 23, 1900.

Application filed February 24, 1900. Serial No. 6,395. (No model.)

To all whom it may concern:

Be it known that I, JOHN JAMES RATHBONE, a subject of the Queen of Great Britain, residing at 111 Messina avenue, West Hampstead, London, England, have invented certain new and useful Improvements in Means and Appliances Connected with Air-Tight Electric-Arc Lamps, of which the following is a specification.

10 This invention relates to bottle electric-arc lamps in which the carbons are inclosed in a glass or globe and as far as possible made air-tight.

For the purpose of my invention I prepare 15 a glass or like bottle, globe, or chimney, in the upper part of which I arrange and fix the upper carbon pencil. The neck of this bottle, globe, or chimney carries, say, a metallic tube insulated or not, as desired, from 20 the lower carbon pencil, which is within and is guided by an inner tube or carbon-holder acting as a central core of a solenoid which is surrounded by a magnet or shunt-coil, single or double, as desired. The lower end of this 25 core is by a light flexible chain or wire connected to the bottom plate of the lamp, which for my purpose may serve as one of the pole-plates, the socket of the upper-carbon capping or clip being the other pole. The light 30 flexible chain or wire connection is of importance in this invention, because its flexibility permits of the lower carbon rising proportionately to the consumption without breaking the current, and the solenoid preserves the regularity of the arc distance of the carbon points. The light flexible chain or its 35 equivalent may be used in conjunction with mercury in the base of the lamp or alone, as found necessary.

40 My invention is illustrated in the sectional elevations on the annexed drawings, in which—

Figure 1 is an arrangement in which a light flexible connection of the lower-carbon holder 45 with the metallic tube is employed, Fig. 2 showing a mercury connection in lieu of the flexible connection.

According to Fig. 1, the upper carbon *a* is fixed in an air-tight manner in a socket *b*, 50 screwed into the metallic capping *c*, on which is mounted the terminal *d*. The bottle-globe *e* is supported and fixed air-tight between the capping *c* and a gallery *f*, forming part of the metallic tube *g*, which is inclosed within an

outer casing *h*, having an enlarged portion *i* 55 for the reception of a shunt-coil *j*, covered by a cap *k*. The lower carbon *l* is fixed in a tubular carbon-holder *m*, serving as a central iron core which is acted upon by the shunt-coil *j* in proportion to the strength of the current passing through said coil, determined by the degree of resistance of the arc between the carbons in the well-known manner. In Fig. 1 this tubular holder *m* is in electrical connection with the metallic tube *g* by means 60 of a light flexible chain or wire *n* at the lower end; but in Fig. 2 the electric connection is effected by mercury *p*, in which the lower-carbon holder *m* is supported or floats under the attraction of the electromagnet. The iron 70 carbon-holder *m* has a small opening *m'* at the base to allow the mercury or its equivalent to slowly enter the holder and act as a dash-pot.

The path of the main circuit will be readily 75 traced from the drawings. It passes from the terminal *q* and traverses tube *g*, chain *n*, (or mercury *p*, Fig. 2,) holder *m*, lower and upper carbons *l* and *a*, socket *b*, and capping *c* to the pole or terminal *d*. The shunt-circuit is 80 from terminal *q*, through coil *j*, along wire *r* to the terminal *d*.

What I claim, and desire to secure by Letters Patent, is—

1. In an electric-arc lamp, the combination 85 of a guide-tube surrounded by a shunt-coil and carrying a suitable liquid, a lower-carbon holder in the form of a central core, a solenoid arranged in said tube and partly supported by said liquid, an air-tight globe carried 90 by said guide, an air-tight capping fitted with a screw-socket connected to the said globe and the lower-carbon holder carried by said capping.

2. In an electric-arc lamp, a lower-carbon 95 holder in the form of a central core of a solenoid, supported in mercury and provided with an opening to permit of the mercury acting in the manner as a dash-pot, substantially as described.

In testimony whereof I have hereunto set my hand in presence of two subscribing witnesses.

JOHN JAMES RATHBONE.
